UNITED STATES PATENT OFFICE.

ALFRED LISTER AND EDWIN LISTER, OF NEWARK, NEW JERSEY.

APPARATUS FOR DRYING GLUE.

SPECIFICATION forming part of Letters Patent No. 228,541, dated June 8, 1880.

Application filed March 2, 1880. (Model.)

To all whom it may concern:

Be it known that we, ALFRED LISTER and EDWIN LISTER, (the firm of LISTER BROTHERS,) both of the city of Newark, in the county of 5 Essex and State of New Jersey, have invented certain new and useful Improvements in Means for Drying Glue; and we do hereby declare the following to be a full, clear, and exact description of the invention, such as 10 will enable others skilled in the art to which it appertains to make and use the same, reference being had to the accompanying drawings, and to letters of reference marked thereon, which form a part of this specification.

15 This invention relates more especially to the means or apparatus employed by us in drying and hardening glue after it has been spread upon nets in the usual manner, our object being to save labor and time and secure better 20 results as compared with the means heretofore in vogue.

In drying the glue we make use of an approximately air-tight chamber, into which the glue is run on carriages, and through which 25 currents of air are impelled by one or more blowers, the air being heated by being directed against a group of pipes heated by steam or otherwise. The temperature of the chamber is regulated and controlled by any appropriate 30 means, and ascertained by means of a thermometer placed within the chamber, the thermometer, as well as the glue, being accessible to the operator through openings in the chamber. The open end of the chamber we provide 35 with a curtain, by raising or lowering of which the temperature of the chamber may be regulated.

A system of elevators, tracks, and carriages is used for elevating and lowering the glue 40 from one floor to another, for conveying it along the outside of the chamber, thence into and through the same, and finally out thereof, all of which we will proceed to more particularly describe.

45 In the accompanying drawings, in which similar letters of reference indicate like parts in each of the several figures, Figure 1 is a perspective view of our apparatus, and Fig. 2 is a plan view of the same, clearly indicating 50 the nature of the invention.

In constructing our apparatus we first build

the air-tight chamber A nearly the full length of our drying-sheds—those we now have in use being about one hundred and twenty feet in length—in which the glue is placed for drying, 55 leaving in one of the side walls forming said chamber A the egress-aperture or doorway B and the windows c, through which the degree of temperature and condition of the glue are readily ascertained, one end, D, being open 60 to allow ingress for the glue-carriages E, and the other end having an opening or openings, a, Fig. 2, for the currents of air coming from the blowers b.

Within the chamber A is the heating or drying apparatus d, placed in front of and in close proximity to the wind passages or inlets a, through which the wind from the blowers b is forced and heated. The chamber also contains the tracks g', upon which the incoming 70 trucks or carriages containing the glue to be dried are transported.

The doorway or egress-aperture B is closed, when the glue is in process of drying, by the door c, and the open end D is covered, when 75 so required, by the curtain f, Fig. 1, which is capable of being rolled up and unrolled at the pleasure of the operator, and serves to aid in regulating the temperature of the inclosed chamber A.

To transport the glue to and from the chamber A we construct very low skeleton trucks or carriages E, which are adapted to be run on tracks g and g', and also adapted to receive the frames h, Fig. 1, upon which the glue 85 is spread. The trucks we now have in operation are constructed to receive three stacks of frames. We pile about twenty deep, each truck or carriage thus carrying about sixty frames. The chamber A being filled with 90 trucks so arranged, an immense quantity of drying-surface is presented to the warm dry wind blowing through the chamber.

The inside or chamber tracks, g', are connected with outside tracks, g, by means of 95 carriages or trucks E', which run upon sunken transverse tracks g'', said transverse tracks being sufficiently sunk below the level of the floor of the building to allow the floor of said truck E' to be upon a level with the floor of 100 said building. The tracks g connect with the elevator F, Fig. 2, upon which the trucks E

are raised or lowered to or from the apartments where the glue is sliced and spread upon the frames to those where it is dried.

Upon each of the several floors of our drying-sheds we have constructed the above-described drying-chamber, with its accompaniments, all connected by tracks of the same gage and by the elevator, and we thus have facilities for drying at the same time different qualities of glue and with varying degrees of heat, in longer or shorter times, as the work may seem to require, without being in any way dependent on the state of the atmosphere outside of the building:

- 5 In operating our invention the glue, after being spread upon the frames *h* in the usual manner, is piled or stacked upon the carriages or trucks *E*, which are then run upon the elevator *F* and raised to the floor upon which the desired drying-chamber is situated. It is then run over the track *g* to the transverse railway, which leads to the open end *D* of the drying-chamber *A*, the truck upon which railway carries it to the track *g'*, which brings it into position in the said drying-chamber. When said chamber *A* is thus filled with trucks bearing glue-frames *h*—in the present case about thirty-five being required—all the apertures are closed and a draft of cold dry air is sent through the chamber *A* to form a “skin” upon the surface of the glue, which prevents the latter from melting and falling through the netting. This being accomplished, the heat is turned on, it being regulated as already stated, and the glue dried, which result will be arrived at in about two and one-half to three days, the old method of drying by the open atmosphere requiring from two to three weeks, and sometimes even six weeks.
- When the glue is dry, which can easily be ascertained through the windows *c*, the trucks or carriages *E* bearing the glue are run out over the transverse railway through the egress-aperture *B*. The dried glue is then stripped from the frames and dumped into the conveyer-

box or chute in the ordinary manner, and runs down into the cracking-mill, and is broken and packed into barrels in the usual way, ready for the market, the empty frames being placed back on the truck, run on the elevator, and dropped down to the bottom floor, ready to be refilled.

We are aware that most of the elements herein described have been used in driers of some kind; but our invention relates more to the arrangement of the several parts than to novelty in the application of any one of the elements.

Having thus described our invention, what we claim, and wish to have secured by Letters Patent, is—

1. In a glue-drier, the combination of a drying-chamber, a heat-radiator, a blower for impelling air against said radiator and then through said chamber, a track and carriage for transporting the glue along the chamber to one end thereof, then through said chamber and out thereof, and an elevator provided with tracks, the several parts being relatively arranged to operate as described.

2. In a glue-drier, the combination of a drying-chamber, a thermometer therein, and a transparent window to observe the same, a heat-radiator, a blower for impelling air against said radiator and then through said chamber, a track and carriage for transporting the glue along the chamber to one end thereof, then through said chamber and out thereof, and an elevator provided with tracks, the several parts being relatively arranged to operate as described.

In testimony that we claim the foregoing we have hereunto set our hands this 24th day of February, 1880.

ALFRED LISTER.
EDWIN LISTER.
